W. E. MORRISON

WINDOW FASTENER

Filed Sept. 9, 1925

UNITED STATES PATENT OFFICE.

WILLIAM E. MORRISON, OF GRANITE CITY, ILLINOIS, ASSIGNEE OF ONE-HALF TO
ISRAEL B. HURWITZ.

WINDOW FASTENER.

Application filed September 9, 1925. Serial No. 55,297.

This invention relates to an improved article of hardware which may be conveniently and specifically designated as a window sash holder or fastener.

5 The invention has more specific reference to a device of this kind which is mounted upon the top of a lower sliding sash and is cooperable with the lower portion of the upper sliding sash for preventing unauthorized 10 opening of the sashes from the outside of the window.

The details of the structure and their relative arrangement and association will become apparent from the following description 15 and drawings.

In the accompanying drawings forming a part of this application, and in which like numerals are employed to designate like parts throughout the same:

20 Fig. 1 is a fragmentary view of a portion of a window showing the improved sash holder in operative position.

Fig. 2 is an enlarged side view in section and elevation showing the specific construction 25 of the holder more plainly.

In carrying out the invention, I employ a mounting bracket 1 which in the present instance comprises an attaching base 2 having upstanding ears 3 through which a pivot 30 pin or bolt 4 extends.

Pivotedly mounted upon the bolt 4 is the improved retainer generally indicated by the reference character 5. This retainer comprises a substantially U-shaped member having a short arm 6 pivoted upon the pin 4 and a long arm 7 extending outwardly beyond the window frame as shown.

The intermediate portion or bight of the U-shaped member is in the form of an arcuate plate 8 carrying a corrugated rubber facing 9. Attached to the free end of the arm 7 is a depending operating chain 10 having a finger piece 11 at its bottom. In addition, a curvilinear or bowed spring 12 is fastened 45 at one end to the base portion 2 of the attaching bracket and has its free end portion overhanging and bearing upon the arm 6 at a point spaced from the pivot connection of the same.

50 Under normal conditions, the spring 12 serves to yieldably hold the facing 9 in locking contact with one of the side rails of the upper sash 13 when the bracket 1 is fastened upon the top of the lower sash 14 as shown. Because of the peculiar shape and

location of the device, it is obvious that when thus positioned, it is impossible to push the upper sash 13 down or to lift the lower sash 14 up. It is obvious, though, that if the upper sash has been lowered 60 somewhat and it is desired to raise and close it, this can be done without interference of the locking device. This is also true of the lower sash; that is, if it has been raised slightly it can be lowered to closed position 65 without interference of the device. It is also obvious that the operator may, at any time, pull upon the operating chain 10 to temporarily hold the device out of operation when the sash is to be raised or lowered 70 as may be desired.

With the device shut, however, considerable difficulty would be experienced in attempting to open the sashes from the interior. It is also evident from the foregoing 75 description that I have evolved and produced a comparatively simple and inexpensive lock that can be put in place by unskilled hands. Although it binds severely, it nevertheless does not mar or destroy the window 80 sash.

The tighter the push against the sashes, the tighter the device binds. The device is not unsightly in any instance and has proven to be successful in operation after considerable 85 actual use.

The foregoing and other features and advantages of the invention have doubtless been made apparent by the description and drawings. Moreover the description will 90 suffice, when taken in connection with the drawings, to enable persons skilled in the art to obtain a clear understanding of the invention. Therefore a more lengthy description is thought unnecessary.

95 While the preferred embodiment of the invention has been shown and described, it is to be understood that minor changes coming within the field of claimed invention may be resorted to if desired.

Having thus described my invention, what I claim as new is:—

The herein described sash fastener comprising a bracket, a vertically swingable U-shaped retainer having an arcuate toothed bight portion adapted for use in opposed relation to a window sash and also having at the lower end of said arcuate portion a short lower arm pivoted at its end remote from the arcuate portion to the said bracket, and

further having a long arm extending in the same vertical plane as the lower arm from the upper end of the arcuate portion and overhanging and spaced from the lower arm 5 and the bracket and extending beyond the pivoted end of the lower arm and the bracket, a string or cable connected to and directly pendent from the end of the long arm, and a bowed spring attached to the 10 bracket below the pivot connection of the lower arm of the retainer and extending upwardly from the point of connection and outwardly beyond the pivot connection of the lower arm and having a free end portion overhanging the pivot connection and the adjacent portion of the lower arm of the retainer and exerting a downward pressure on said lower arm; said free end portion of the spring resting in the space between the lower and upper arm, whereby it is protect- 15 ed by the upper arm. 20

In testimony whereof I affix my signature.

WILLIAM E. MORRISON.
